UNITED STATES PATENT OFFICE.

WALTER L. ABEL, OF HOMINY, OKLAHOMA.

AUTOMATIC SHUT-OFF VALVE.

Application filed November 15, 1927. Serial No. 283,390.

This invention relates to improvements in shut-off valves which are designed to shut off the flow therethrough of gas or liquid under pressure.

5 The primary object of the present invention is to provide an improved valve which will automatically shut off the flow of gas or liquid therethrough when the pressure of the latter unduly lowers or discontinues from 10 any cause, and which will thereafter continue to act as a positive shut-off for said flow until said valve is manually opened.

A further object is to provide an automatic shut-off valve that shall be positive 15 in action, simple in construction, not liable to readily get out of working order, and cheap to manufacture.

The invention consists in the novel form, combination and arrangement of parts hereinafter more fully described, shown in the accompanying drawing and claimed.

In the drawing:

Figure 1 is a side elevational view of a shut-off valve embodying the present invention.

Figure 2 is a central vertical sectional view thereof;

Figure 3 is a transverse horizontal section on line 3-3 of Figure 1; and

30 Figure 4 is an elevational view of the movable valve element, and illustrating a modified form of stem for the piston of said element.

Referring more in detail to the drawing, 35 5 indicates an upright cylindrical casing closed at the top by a screw cap 6 and having a side inlet connection 7 and a bottom outlet connection 8 for being respectively coupled or connected to gas or fluid supply and outlet pipes. The casing has a bottom outlet port formed to provide a seat 11 for a 40 downwardly seating weighted ball valve 12 which is suspended by a chain 12^a from a hollow piston 12^b having a rigid rod or stem 45 13 that is arranged axially of the casing 5. The inlet port of the connection or nipple 7 is disposed intermediate the ends of the casing, as shown.

The piston 12^a is fitted and reciprocable 50 in the casing 5, and the ball valve 12 normally lowers by gravity to closed or seated position with the piston disposed below the side inlet as shown by dotted lines in Figure 2.

The stem 13 slidably projects upwardly 55 through a central aperture 18 in the cap 6 as well as through a hollow boss 19 on said

cap, where it terminates above the upper end of the boss to be grasped for lifting the stem and opening the ball valve against the weight of the latter.

60 A hollow elongated cap 21 is detachably carried by the boss 19 to cover the upper terminal or end of the valve stem and prevent ready tampering with said stem.

In operation, the cap 21 is removed and 65 stem 13 is lifted to open the valve 12 with piston valve 12^b disposed above the inlet port, so that unobstructed flow of the gas or liquid may be had through the casing 5 when the outlet line is opened. The pressure of the gas 70 or liquid acting on the under side of the piston 12^b will result in retaining the valve open as long as the pressure is maintained in the supply line or in not unduly lowered therein. Should the pressure be discontinued or 75 unduly lowered from any cause, the weight of ball valve 12 will cause the latter to lower to closed position on seat 11, and should the pressure be thereafter continued again or raised to normal, the same will act on top of 80 piston 12^b and hold the valve closed. It is, therefore, evident that the flow of the gas or liquid will be effectively cut off until the valve 12 is again manually opened.

The lowering movement of piston 12^b may 85 be limited by internal stop lugs 22 on casing 5 below the inlet connection 7.

The under side of cap 6 is preferably recessed about the opening 18 to form a concavo-spherical seat 23, and the top 24 of piston 12^b is shaped to fit and engage this seat, when raised, so as to prevent leakage of the gas or fluid out through opening 18 should it possibly leak between the casing and the piston when the valve is open.

If desired, the cap 21 may be dispensed with, and the upper end of stem 13 may be formed with a finger piece or loop 25 to facilitate grasping thereof to open the valve, as shown in Figure 4.

100 Minor changes may be made without departing from the spirit and scope of the invention as claimed.

What I claim as new is:

1. An automatic gas or liquid shut-off valve comprising an upright cylindrical casing closed at its upper end and having a side inlet port and a bottom outlet port, a stem disposed axially of the casing and having a rigid piston at its lower end, a weighted ball 105 valve suspended from the piston and adapted to seat downwardly to normally close said

outlet port, said stem slidably projecting through the top of the casing, said piston being adapted to move above the inlet port when the valve is raised to open position and being slidably fitted in the casing, the top of the casing being formed with a seat on the under side thereof about the stem, said piston being adapted and shaped at the top to engage the latter seat when the valve is opened to prevent leakage through the top of the casing.

2. In an automatic gas or liquid shut-off valve comprising an upright cylindrical casing closed at its upper end and having a side

inlet port and a bottom outlet port, a stem disposed axially of the casing and having a rigid piston at its lower end, a weighted ball valve suspended from the piston and adapted to seat downwardly to normally close said outlet port, said stem slidably projecting through the top of the casing, said piston being adapted to move above the inlet port when the valve is raised to open position, and being slidably fitted in the casing, and internal stop lugs on the casing below the inlet port for limiting the lowering movement of the piston.

In testimony whereof I affix my signature.

WALTER L. ABEL.
